United States Patent Office.

JOSEPH SHOLL, OF BURLINGTON, NEW JERSEY.

Letters Patent No. 67,457, dated August 6, 1867.

IMPROVEMENT IN FURNACES.

The Schedule referred to in these Letters Patent and making part of the same.

TO ALL WHOM IT MAY CONCERN:

Be it known that I, JOSEPH SHOLL, of Burlington, New Jersey, have invented certain improvements in Furnaces and Flues for Boilers, Ovens, etc.; and I do hereby declare the following to be a full, clear, and exact description of the same.

My invention consists of the combination of a boiler or oven, a fire-box enclosed in an air-chamber, and a flue or passage through which heated air from the said chamber is caused to traverse, in contact with those parts of the boiler or oven not heated directly by the gases from the fire-place; and the invention further consists in the combination of the above and a flue for conveying the air, after its passage round the boiler or oven, to the fire-place, where it assists in consuming the gases.

In order to enable others skilled in the art to make and use my invention, I will now proceed to describe the mode of carrying the same into effect, reference being had to the accompanying drawing, which forms a part of this specification, and in which—

Figure 1 is a vertical elevation of a furnace and steam-boiler with my improvements.

Figure 2, the same, with the boiler removed.

Figure 3, a sectional elevation on the line 1-2, fig. 1.

Figure 4, a sectional elevation on the line 3-4, fig. 1.

Figure 5, a sectional plan on the line 5-6, fig. 2.

Figure 6, a sectional plan on the line 7-8, fig. 2; and

Figure 7, an inverted plan view of part of the furnace.

The outer casing of the furnace consists of the side walls or plates A A', the front and back walls or plates B B', and the curved top C; and within this casing is a cylindrical boiler, D, a horizontal flue, a, which communicates at the front end with a vertical pipe or chimney, a', extending through the shell of the boiler and through the top of the furnace. The fire-place of the furnace, below the front end of the boiler, consists of two oblong fire-boxes E E, which are situated within an air-chamber, X, and which have the usual grates b b; and in the front wall or plate B of the furnace are openings x, through which the air can pass to the chamber X. At each side of the furnace is a jacket or casing, F, which is divided by a vertical partition, c, into two flues or passages y y', the former communicating through an opening, u, fig. 4, with the chamber X, and the latter through an opening, s, with the fire-place, fig. 3. Between the top of the boiler and the arched top of the furnace extend three partitions t t t', which are arranged as shown in fig. 7, so as to form at each side of the central partition t' two parallel flues or passages Y Y', communicating with each other near the rear end of the boiler, the flues Y communicating with the passages y, and the flues Y' communicating with the passages y', fig. 2. Between the rear end of the boiler and the wall or plate B' of the furnace, above the flue a, is a partition, v, fig. 1. The products of combustion from the fire-place pass beneath the boiler to the flue a, and through the latter to the pipe a', heating the lower portion of the boiler and its contents. The air which enters the chamber X becomes highly heated and passes through the openings u and passages y and flues Y to the rear end of the boiler, then back to the front end of the latter, through the flues Y', and thence downward through the passages y', and through the openings s, to the fire-place, fig. 2, where it aids in effecting a perfect combustion of the gases.

By this arrangement the heat radiated from the fire-boxes, which would otherwise be wasted, is utilized for heating those parts of the boiler which are generally exposed to the air, or are covered with jackets of *feit* or other material, while a thorough combustion of the products of combustion is effected within the fire-place and beneath the boiler.

This invention is applicable to vertical boilers, open tanks, and drying or baking-ovens, the flues in each case being arranged in such a manner as may be best-adapted for distributing the heat to the parts where it is required.

Without confining myself to the precise construction and arrangement of parts herein described, I claim as my invention, and desire to secure by Letters Patent—

1. The combination of a boiler or oven with a fire-box enclosed in an air-chamber, and a flue or passage through which heated air from the said chamber is caused to traverse, in contact with those parts of the boiler

not heated directly by the products of combustion from the fire-place, all substantially as and for the purpose described.

2. The combination of the above and a flue for conveying the air, after its passage round the boiler or oven, to the fire-place.

In testimony whereof I have signed my name to this specification in the presence of two subscribing witnesses,

JOSEPH SHOLL.
